H. W. BUNDY.
STEERING WHEEL.
APPLICATION FILED JAN. 2, 1920.

1,375,128.

Patented Apr. 19, 1921.

UNITED STATES PATENT OFFICE.

HARRY W. BUNDY, OF DETROIT, MICHIGAN.

STEERING-WHEEL.

1,375,128.

Specification of Letters Patent. Patented Apr. 19, 1921.

Application filed January 2, 1920. Serial No. 348,902.

To all whom it may concern:

Be it known that I, HARRY W. BUNDY, a citizen of the United States, residing at Detroit, in the county of Wayne and State of Michigan, have invented certain new and useful Improvements in Steering-Wheels, of which the following is a specification.

This invention relates to steering wheels and especially steering wheels for automobiles. It has for its object a steering wheel that can be made up of tubing and provided with a stamped spider in which the hub is secured to the spider members by a pressing operation. The ends of the spider arms can be secured to the tubing forming the rim by notching the under side of the tubing and welding the arms thereto. These features will better appear when a detailed description has been given.

20 In the drawings,—

Figure 1 is a cross section of the steering wheel.

Fig. 2 is a top plan view.

Fig. 3 is an enlarged cross section through 25 the hub after the inner hub member has been bored and slotted.

Fig. 4 is a detail of the under side of the rim after it has been notched to receive the spider arm end.

30 *a* designates the tubing forming the rim. This may be seamless tubing, or so far as the purpose of this invention is concerned, may be tubing formed in numerous ways, such as lock-seam, welded, brazed or other 35 tubing formed into circular cross section. The ends of the tubing are welded together at *b* to form the rim. On the under side of the tubing notches *c* are cut to receive the ends of the spider arms *d*. These spider

40 arms *d* are in the form of pairs of stamped metal strips which are ribbed longitudinally for the main portion of their length with ribs *e* but which at their ends are flattened to form the end portions *f*. At their centers 45 the spider arms are punched and stamped to form the bosses *g* and *h* on the upper and lower pairs of spider arms respectively. The flattened center portions surrounding the bosses lie in overlapped relation as at *i*.

50 The hub is formed of a piece of cylindrical stock *j* which can be formed by a screw machine. This is provided with a knurl that is shown at *k* in Fig. 1. The upper and lower portions of the piece of stock that is to 55 form the hub can be grooved with annular

grooves *l*. This can all be done on a screw machine.

The piece of stock can be placed in the center bosses of the spider arms which are slightly larger than the piece of stock to 60 enable them to readily fit in place. The bosses may then be clamped tightly upon the stock by a suitable press operation which serves to punch the bossed stock into the annular groove *l* and also causes the bossed 65 stock to bite into the knurled portion of the piece of stock that is to form the hub. The interengagement of the stock of the bosses and the hub stock serves to lock the spider arms to the hub stock so that they cannot 70 slip longitudinally thereof, while the interengagement of the bosses with the knurled portions of the hub stock serves to lock the spider arms from turning on the hub stock. It will readily be understood that the upper 75 pair of spider arms having been locked in this way to the upper portion of the hub and the lower pair of spider arms having been locked to the lower portion of the hub, no further locking arrangement between these 80 two pairs of spider arms is required and it will not be necessary to rivet them together, to braze them or weld them.

After the piece of hub stock has been 85 locked into the spider arms in this way the ends of the spider arms *f* may be inserted in the slots *c* of the under side of the rim and welded thereto.

After the spider arms have been assembled upon the rim the hub may be bored and 90 slotted with a key slot, this being effected after the assembly which insures it being correctly centered with respect to the rim.

What I claim is:

1. A steering wheel spider, comprising a 95 plurality of spider arms, a hub made up of a cylindrical member having a depression therein, the said cylindrical member adapted to pass through the center of the steering arms and be secured thereto by pressing the 100 stock of the steering arm into the said depression.

2. A steering wheel spider made up of a plurality of steering arms having a boss at the center, a hub provided with a groove and fitting into the boss, said hub and boss being locked together by pressing the stock of the boss into the groove of the hub. 105

3. A steering wheel spider, having a plurality of spider arms which form a boss at 110

the center, and a hub provided with a groove and a roughened outer surface, said boss being pressed upon the roughened surface of the hub and into the groove to lock the hub in place.

4. A steering wheel spider, comprising a plurality of spider arms having at their center a boss, and a hub locked therein by having a roughened outer surface into which the stock of the boss is pressed.

5. A steering wheel spider, comprising a plurality of spider arms forming at their center a boss, and a hub provided with a knurled outer surface and locked into the boss of the steering arms by pressing the stock of the boss into the knurled surface of the hub.

6. A steering wheel spider, comprising a plurality of steering arms forming at the center a boss, and a hub provided with an annular groove formed therein, the said stock of the boss pressed into said annular groove to lock the hub into the steering arms.

7. A steering wheel spider made up of a pair of steering arms formed at their centers with hub openings and bosses and overlapped, and a hub locked thereinto by pressing the bosses into the substance of the hub.

8. A steering wheel spider made up of spider arm pairs punched and bossed at their centers and overlapped, and a hub having an outer surface onto which the stock of the two bosses are adapted to be pressed to lock the hub therein and lock the two pairs of arms together.

9. A steering wheel spider, comprising two pairs of steering arms punched and bossed at their centers and overlapping, and a hub having at each end a groove, the substance of the two bosses being adapted to be pressed into the two grooves to lock the hub into the arms and the two pairs of arms together.

10. A steering wheel spider made up of two pairs of arms punched and bossed at their centers and overlapped, and a hub having an annular groove cut in each end and the substance of the two bosses pressed in the two annular ends to lock the hub in place and the two pairs of spider arms together.

11. A steering wheel spider, having in com-

bination, two pairs of steering wheel arms punched, bossed and overlapped at the center, and a hub roughened on the exterior and grooved at each end and adapted to be fitted into the bosses and the stock punched to fit into the grooved ends.

12. The method of constructing steering wheel spiders, comprising the stamping of the spider arms in pairs with center bosses, the roughening of the exterior of the hub, the insertion of the hub in the perforate central bosses, and the pressing of the bosses upon the hub to lock the hub to the spider arms and the spider arms together.

13. The method of constructing steering wheel spiders, comprising the stamping of the spider arms in pairs with central perforated bosses, the knurling of the hub and inserting it in the bosses, and the pressing of the bosses upon the knurled hub to lock the hub into the spider arms and the spider arm pairs together.

14. The method of constructing steering wheel spiders, consisting of stamping the spider arms with central perforated bosses, the roughening of the exterior of the hub and inserting it in the overlapped central bosses of the spider arms, and the pressing of the stock of the bosses upon the roughened portion of the hub to lock the hub to the arms and the arms to one another.

15. The method of constructing steering wheel spiders, comprising the stamping of the spider arms with perforate central bosses, the grooving of the hub and inserting the same in the overlapped perforated central bosses of the spider arms, and the pressing of the bosses into the grooves of the hub to lock the hub into the spider arms and the spider arms together.

16. The method of constructing steering wheel spiders, comprising the stamping of the spider arms with perforated central bosses, the roughening of the grooving and the exterior of the hub and inserting it in the overlapped central perforated bosses of the spider arms, and the pressing of the stock of the bosses into the grooves and roughened exterior of the hub to lock the hub to the arms and the arms together.

In testimony whereof I affix my signature.

HARRY W. BUNDY.
